UNITED STATES PATENT OFFICE.

WILLIAM S. ROATH, OF CANTON, OHIO.

WATER-HEATER.

SPECIFICATION forming part of Letters Patent No. 784,964, dated March 14, 1905.

Application filed September 28, 1904. Serial No. 226,304.

To all whom it may concern:

Be it known that I, WILLIAM S. ROATH, of the city of Canton, county of Stark, and State of Ohio, have invented new and useful Improvements in Water-Heaters, of which the following is a specification.

The invention relates to water-heaters made of a series of vertical sections assembled side by side; and the principal objects of the improvements are to arrange the waterways so as to present the maximum heating-surface with reference to the grate area; to carry the fire-gases without separation along the waterways and not across them in the first instance and then to accumulate the gases in a common superheating-chamber around the water-tubes above the smoke-flue to permit a complete combustion; to arrange the waterways so the heated water will travel in one direction only from the several locations to the top of the heater to create a free and definite circulation; to directly join the sections by nipples at the lowest and highest points, so water of different temperatures will flow freely and equalize between the several sections, and to construct and arrange the parts so that all the heating-surfaces can be readily reached for cleaning. These objects and other minor ones are attained by the construction and arrangement illustrated in the accompanying drawings, in which—

Figure 1 is a side elevation of an intermediate section of the heater with the adjacent and adjoining parts thereof in section; Fig. 2, a front elevation of a heater made of three intermediate and two side sections with parts broken away to show some details in cross-section; Fig. 3, a vertical longitudinal section of one of the intermediate sections; Fig. 4, a section of the heater on line 4-4, Fig. 1; Fig. 5, a section of the heater on line 5-5, Fig. 1; Fig. 6, a fragmentary side view showing an alternate way of connecting the smoke-pipe to the breeching; Fig. 7, a detached perspective view of the middle intermediate section, and Fig. 8 a similar view of one side section with parts broken away to show some details in section.

Similar numerals refer to similar parts throughout the drawings.

The intermediate sections 1 and 1^a are each provided with an exterior waterway forming a rim for the section, which rims when abutted laterally constitute the back, top, and, above the fire-box 2, the front of the heater. 55 Each exterior way comprises the stemway 3, extending along the back of the fire-box, the back way 4, preferably extending first rearward and then directly upward along the back of the heater, the top way 5, inclining along 6c the top of the heater from the rear way upward to about the middle, thence downward to the front thereof, and the front way 6, extending directly downward along the front of the heater to the top of the fire-box. In the 65 lower end of each stemway are provided the lateral apertures 7, and in the middle and highest part of each top way are provided the similar lateral apertures 8, in which apertures the nipples 9 are inserted when the sections are 70 brought together, thus making two continuous lateral channels, one at the bottom and one at the top of the heater, by means of which channels the water can circulate freely from one section to another. One or more 75 of the intermediate sections is provided with an inlet-aperture 10 in the back wall of the stemway, preferably opposite the nipple-apertures, in which inlet-aperture is connected the inlet-pipe 11 for the return of the colder 80 water from the heating system, (not shown,) and also with an outlet-aperture 12 in the top wall of the top way, at the highest part thereof, in which aperture is connected the outlet-pipe 13 for the flow of heated water 85 into the heating system.

The interior waterways comprise the tube-ways 14, 14^a, and 14^b and the baffle-ways 15 and 16, which are inclined upward and forward and communicate from the back way to 90 either the front way or top way, as illustrated. The tube-ways are formed less in diameter than the width of the exterior ways, so that when the sections are assembled there is quite an interval between the tube-ways. The baffle-ways, however, are of the same width as the exterior ways, so that these ways abut side by side when the sections are assembled and constitute two laterally-continuous baffle-walls 95 15^a and 16^a. The rear ends 15^b of the lower 100

baffle-ways 15 are reduced to the width of the tubeways, so that the fire-gases can pass around the rear ends of the baffle-wall 15^a and through the intervals thus formed, and the 5 forward ends 16^b of the upper baffle-ways 16, together with the considerable portion 6^a of the front ways 6 above the lower baffle-plate, are reduced to the width of the tubeways, so that the fire-gases can pass around the forward 10 end of the baffle-wall 16^a through the intervals thus formed. The doors 17 are hinged on the front of the heater and normally close the intervals in the front wall; but when these doors are opened these intervals give 15 access to all the heating-surfaces of the several tubes and baffle-ways above the lower baffle-plate for cleaning the same. The heating-surfaces below the lower baffle-plate can be readily reached from the fire-box. The parts 20 4^a of the back ways near and above the upper baffle-ways are reduced to the width of the tubeways, and the intervals between these reduced parts make an outlet for the smoke and other products of combustion. The breeching 25 18 is attached to the back of the heater, so as to cover all the smoke intervals in the back, and by attaching the reducing-elbow 19, as shown in Figs. 1 and 5, the smoke-pipe 20 can be directed upward, or by attaching it as 30 shown in Fig. 6 the smoke-pipe can be directed rearward.

Each side section 21 is formed with one half just like the adjoining intermediate section, and the several tubes and baffle-ways are 35 connected in their middle lines by the short partitions 22, from which partitions the outer walls 23 of the side sections and of the heater are spaced at an interval to form the side ways 24, which extend over the entire sides 40 of the heater. The side sections and side ways are extended downward and forward to form the side walls 25 of the fire-box, and it is preferred to connect the lower forward corner of these sections by the crossway 26, having 45 communicating nipples, as at 27. The sections of the heaters are held together by the tie-rods 28 passed through the lugs 29 on the side sections, and the door 30 is hinged on the front of the heater to close the fire-box. The heater thus assembled is preferably 50 set on a suitable base, as 31, which forms an ash-pit, and the bottom of the fire-box is provided with the usual grate-bars 32.

When the gases rise from the fire, they travel 55 first upward and backward along and around the tubes 14, being so diverted by the baffle-plate 15^a, thence upward around the reduced rear ends 15^b of the baffle-ways and forward along and around the tubeways 14^a, being so 60 diverted by the baffle-plate 16^a, thence upward along and around the reduced parts 6^a of the front ways and the reduced forward ends 16^b of the baffle-ways 16 into the superheating-chamber formed by the intervals 65 around the tubeways 14^b. The gases then

travel backward along and around the tubeways 14^b to the smoke intervals between the reduced parts 14^a of the back ways and on through the breeching and smoke-pipe. As the fire-gases travel through the heater they 70 are not separated at any point except as they surround the various tubeways, and as a result they are free to mingle and combine in the proper proportions for complete combustion. This is specially true of that part of the 75 heater above the smoke-apertures, wherein unburned gases are retained until proper proportions are present to cause complete combustion, and for this reason this chamber is well named a "superheating-chamber." 80 Gases are thus utilized which would ordinarily pass out unburned through the smoke-pipe.

As the water is heated in the several interior ways it naturally flows upward and forward to the front ways, thence upward in the front ways and rearward in the forward part of the top ways to the highest parts thereof, from which it passes upward into the heating system through the outlet-pipes. The cooled 90 water in the heating system naturally flows downward and enters the heater through the inlet-pipes into the lower ends of the stem-ways, from which it ascends, some of it through the back ways, and passes into the rear lower 95 ends of the interior ways. The cooler water within the heater naturally flows downward to and through the back ways until water of equal temperature is reached, which is joined, and the upward forward flow through the interior ways is resumed.

What I claim as my invention, and desire to secure by Letters Patent, is—

1. A water-heater comprising a series of vertical sections between water-containing side sections, the intermediate sections having laterally-abutting waterways forming the back, top and front of the heater, the top ways being inclined upward from front and rear to the middle, abutting baffle-ways communicating and inclined upward from the back to the front ways, and similarly communicating and inclined tubeways at intervals apart, and below, between and above the baffle-ways, the alternate ends of the baffle-ways being reduced in width to make intervals therebetween for the passage of fire-gases, and parts of the back ways near and above the upper baffle-ways being likewise reduced to make intervals therebetween for smoke-outlets, and the parts of the front ways above the lower baffle-ways being likewise reduced to make intervals for cleaning, there being communicating apertures between the upper parts of the top ways and the lower ends of the back ways, and inlet and outlet pipes connected in the lowest and highest parts of the waterways. 120

2. A water-heater comprising a series of vertical sections between water-containing side sections, the intermediate sections having 130

laterally - abutting waterways forming the back, top and front of the heater, the top ways being inclined upward from front and rear to the middle, abutting baffle-ways communicating and inclined upward from the back to the front ways, and similarly communicating and inclined tubeways at intervals apart, and below, between and above the baffle-ways, the alternate ends of the baffle-ways being reduced in width to make intervals therebetween for the passage of fire-gases, and parts of the back ways near and above the upper baffle-ways being likewise reduced to make intervals therebetween for smoke-outlets, there being communicating apertures between the upper parts of the top ways and the lower ends of the back ways, and inlet and outlet pipes connected in the lowest and highest parts of the waterways.

3. A water-heater comprising a series of vertical sections between water-containing side sections, the intermediate sections having laterally - abutting waterways forming the back, top and front of the heater, the top ways being inclined upward from front and rear to the middle, abutting baffle-ways communicating and inclined upward from the back to the front ways, and similarly communicating and inclined tubeways at intervals apart, and below, between and above the baffle-ways, the alternate ends of the baffle-ways being reduced in width to make intervals therebetween for the passage of fire-gases, and parts of the back ways near and above the upper baffle-ways being likewise reduced to make intervals therebetween for smoke-outlets, there being inlet and outlet pipes connected in the lowest and highest parts of the waterways.

4. A water-heater comprising a series of vertical sections between water-containing side sections, the intermediate sections having laterally - abutting waterways forming the back, top and front of the heater, the top ways being inclined upward from front and rear to the middle, abutting baffle-ways communicating and inclined upward from the back to the front ways, and similarly communicating and inclined tubeways at intervals apart, and below, between and above the baffle-ways, the alternate ends of the baffle-ways being reduced in width to make intervals therebetween for the passage of fire-gases, and parts of the back ways near and above the upper baffle-ways being likewise reduced to make intervals therebetween for smoke-outlets.

5. A water-heater comprising a series of vertical sections between water-containing side

sections, the intermediate sections having laterally-abutting waterways forming the back, top and front of the heater, alternating adjacent tubeways and abutting baffle-ways with a series of adjacent tubeways thereabove all communicating and inclined upward from the back to the front ways, the alternate ends of the baffle-ways and parts of the back ways near and above the upper baffle-ways being reduced in width to make intervals therebetween for the passage of fire-gases and smoke.

6. A water-heater comprising a series of vertical sections between water-containing side sections, the intermediate sections having laterally-abutting waterways forming the back, top and front of the heater, a series of abutting baffle-ways with a series of adjacent tubeways thereabove all communicating and inclined upward from the back to the front ways, the alternate ends of the baffle-ways and parts of the back ways near above the upper baffle-ways being reduced in width to make intervals therebetween for the passage of fire-gases and smoke.

7. In a sectional water-heater, a baffle-plate inclined upward and forward from the back with intervals at the forward end for the passage of fire-gases, and a gas-retaining chamber above the baffle-plate having a series of adjacent and similarly-inclined tubeways therein, there being a smoke-outlet in the back from the lower part of the chamber.

8. In a sectional water-heater, a vertical section having back, top and front waterways, the top way being inclined upward from front and rear to the middle, baffle-ways communicating and inclined upward from the back to the front ways, and similarly communicating and inclined tubeways at intervals below, between and above the baffle-ways, the alternate ends of the baffle-ways being reduced in width.

9. In a sectional water-heater, a vertical section having back, top and front waterways, baffle-ways communicating and inclined upward from the back to the front ways, and similarly communicating and inclined tubeways at intervals below, between and above the baffle-ways, the alternate ends of the baffle-ways being reduced in width.

In testimony whereof I have hereunto signed my name to this specification in the presence of two subscribing witnesses.
